UNITED STATES PATENT OFFICE.

JOHN H. BICKFORD, OF SALEM, MASSACHUSETTS, ASSIGNOR OF ONE-THIRD
TO S. FREDERICK SMITH, OF SAME PLACE.

SEAL.

SPECIFICATION forming part of Letters Patent No. 394,531, dated December 11, 1888.

Application filed April 3, 1888. Serial No. 269,466. (No model.)

To all whom it may concern:

Be it known that I, JOHN H. BICKFORD, of Salem, county of Essex, and State of Massachusetts, have invented an Improvement in Seals, of which the following description, in connection with the accompanying drawings, is a specification, like letters on the drawings representing like parts.

This invention has for its object to construct a seal for freight-car doors and the like which cannot be easily tampered with by malicious persons, and if tampered with will be destroyed, so as to be easily traceable.

In accordance with this invention I employ a longitudinally-grooved metallic block having two holes communicating with the groove, and also a wire loop having its ends bent to enter the groove and holes of the said block. A compressible bar or block is also employed, shaped to fit the groove above or upon the bent ends of the wire loop, said block, when compressed, holding the ends of the loop rigidly in position. The compressible block is preferably made of lead, and the ends of the wire loop are fitted into the metallic holding or connecting block at a short distance apart, so that the material of the compressible block, when compressed, enters slightly the space between the said ends as well as fills the groove flush. The groove is preferably of dovetail shape in cross-section, in order that the compressible block may be readily placed therein and held.

Figure 1 shows in front elevation and partial section a seal embodying this invention; Fig. 2, a vertical section of the seal shown in Fig. 1, taken on the dotted lines $x-x$; Fig. 3, a vertical section of a portion of the seal shown in Fig. 1, taken on the dotted line $y-y$; Fig. 4, a horizontal section of the seal shown in Fig. 1, taken on the dotted line $z-z$; Fig. 5, an under side view of the seal shown in Fig. 1, the compressible block being removed; Figs. 6 and 7, details of the compressible block; Fig. 8, a front elevation and partial section of the seal shown in Fig. 1, the block being compressed; Fig. 9, a ver-

tical section of a portion of the seal shown in Fig. 8, taken on the dotted line $2-2$; Fig. 10, an under side view of the seal shown in Fig. 8.

The loop a , of wire or other suitable material, is bent as desired, the ends of the wire being bent inwardly and terminating a short distance from each other. The connecting-block b , of hard metal, has a dovetailed groove, b' , formed upon one side longitudinally, and is provided with two holes, (see Fig. 1,) into which, from inside the said groove, enter the ends b^2 of the wire loop.

The compressible fastening employed is herein shown as consisting of a bar or block, c , of soft metal—as lead—shaped to fit the groove b' of the connecting-block, the fastening being bent outwardly at its center, (see Fig. 1,) where it has a face, c' , upon which a number or other character may be impressed, as in Fig. 10.

The soft-metal fastening-block c is placed in the groove b' of the block b after the ends b^2 have been extended through the connecting-block, thereby holding the wire loop in place. The soft-metal block or bar is then compressed by any suitable implement to force the material thereof into and to fill the dovetail groove b' of the connecting-block b , so that the face of the soft-metal block will lie flush with the face of the hard-metal connecting-block.

Any suitable numbers or letters may be impressed into the soft-metal block to characterize the seal.

In shipping the seals to be used the soft-metal blocks are held in place in the groove of the hard-metal block, and when it is desired to use the seals the soft-metal block is removed, the loop removed from the hard-metal block, and placed over or through the loop or eye of the fastening that it is desired to seal. The ends b^2 are then made to enter the holes of the block b . The soft-metal block is returned into place and thereafter compressed.

I claim—

In a seal, the loop a and connecting-block longitudinally grooved or cut away upon its

under side, and having holes to receive the upturned ends of the loop, combined with a compressible block adapted to enter the said groove or cut-away portion of the connecting-block and to be compressed therein, substantially as described.

In testimony whereof I have signed my name

to this specification in the presence of two subscribing witnesses.

JOHN H. BICKFORD.
